UNITED STATES PATENT OFFICE.

WILLIAM DOUGLAS CARTER, OF SAN JOSE, CALIFORNIA.

CENTRIFUGAL, TURBINE, AND SIMILAR PUMP.

1,260,639.

Specification of Letters Patent.

Patented Mar. 26, 1918.

Application filed May 29, 1916. Serial No. 100,712.

To all whom it may concern:

Be it known that I, WILLIAM DOUGLAS CARTER, a citizen of the United States, residing in San Jose, in the county of Santa Clara and State of California, have invented certain new and useful Improvements in Centrifugal, Turbine, and Similar Pumps, of which the following is a specification.

10 This invention relates to an improved construction for centrifugal, turbine, or similar pumps of those types known as multi-impeller and multi-stage pumps, in the former of which the two or more impellers operate in parallel, and in the latter in series.

The object of this invention is to effect readily in one pump the combination of several impellers in series, parallel, or 20 multiple series, so that the pump may have a wider range of efficient service, without the necessity of a change of speed. This quality is particularly desirable in pumps which are directly connected to constant speed motors, and it makes it possible to manufacture cheaply single speed directly connected stock pumps which can be used efficiently for a great many different conditions of service.

30 The nature and scope of this invention are more fully explained in the following description, taken in connection with the accompanying drawings forming part hereof, in which,

35 Figure 1 is a cross section taken on line 1 of Fig. 2, of a pump having a specially constructed double service impeller which operates in effect as two separate impellers. Fig. 2 is a longitudinal section of the above 40 pump with side of pump and part of discharge opening shown in full. Fig. 3 is a cross section taken on line 2 of Fig. 4 of a similar pump having two double service impellers supported on a single shaft. Fig. 4 is a longitudinal section of pump shown in Fig. 3, with part of one side containing suction and discharge openings shown in full. Fig. 5 is a cross section taken on line 45 3 of Fig. 6, also showing in full the suction and discharge flanges and part of end view of a differently constructed pump having two single impellers. Fig. 6 is a longitudinal section of the last mentioned pump with part of suction opening and side shown in full. Fig. 7 is a top view of Fig. 6. Figs. 50 8 and 9 are sectional views, similar to Figs. 1 and 2, but showing the casing C turned to a position where a series flow through the double runner is permitted.

Similar letters refer to similar parts 60 throughout the several views.

In Figs. 2 and 4 specially constructed double service impellers are shown making the pump design more compact; but it will be observed that in so far as the flow of 65 water through the pump is concerned, the operation is the same as where two or more separate impellers are employed.

Referring particularly to Figs. 1 and 2, I is a double service impeller designed with 70 two separate passages E and O so that the flow of water in either half is independent of the flow in the other half. F is the pump shaft carrying impeller I. Surrounding impeller I is a movable cylindrical casing C 75 containing suction passage K with opening or port L, and symmetrically arranged discharge passages N and P with ports Q and R respectively. Said ports L, Q, and R are arranged in a longitudinal row in the outside surface of said cylindrical casing C. M is a base with a cylindrical surface or seat J which supports and closely fits the outside cylindrical surface of casing C. Base M contains manifold passages with main suction opening S, and main discharge opening 80 D, and other openings or ports in said cylindrical seat J which are either closed by the cylindrical surface of casing C, or are connected with said ports L, Q, and R in casing 85 C, according to the relative position of said casing C on said cylindrical seat J. Suction passage T permanently connects suction opening S with passage O of impeller I. The longitudinal axis of cylindrical seat J, 90 and the longitudinal axis of cylindrical casing C are concentric with that of impeller I and shaft F, so that casing C may be rotated on seat J without interfering with the rotation of impeller I and shaft F. When casing C has been rotated on cylindrical seat J until ports L, Q, and R coincide with the 95 ports of manifold passages in base M selected to connect the passages of impeller I in series or in parallel, as service conditions 100 may require, screw U is tightened so as to hold casing C in its selected position. Receptacle V which is formed by an extension of the sides of base M may be filled with water in order to seal the joint formed between the outside cylindrical surface of casing C and cylindrical seat J and thereby 110

prevent the leakage of air into passages of casing C or manifold in base M which may be below atmospheric pressure.

- When it is desired to operate the two halves of impeller I in parallel so as to discharge the combined volume of water against the same pressure as that created by either half of impeller singly, casing C is locked in position shown in Figs. 1 and 2.
- 10 The flow of water is then as shown by the arrows: Entering at suction opening S part of the water goes through passage T to passage O of impeller I, and the remainder through manifold passage W, port L 15 and passage K to passage E of impeller I. Discharge passages P and N conduct the water received under equal pressure from passages O and E of impeller I through ports R and Q respectively to main discharge opening D.

When on the other hand it is desired to operate the two halves of impeller I in series so as to discharge half of the above volume against the combined pressures created independently by the two halves of impeller I, then casing C is moved to the position shown in Figs. 8 and 9 and the flow of water is as shown by the arrows. Referring to both Figs. 8 and 9, water entering at main suction 25 opening S, follows along the course shown by the arrows through passage T to passage O of impeller I, thence through discharge passage P and port R to manifold passage X which conducts the water through port L 30 and passage K of casing C to passage E of impeller I which in turn adds its supply of pressure energy to the water, and discharges through N as indicated and out main discharge opening D. It is thus possible without changing in any manner the piping connected with the main suction or discharge openings of the pump, and without even stopping the rotation of impeller I, to make said pump deliver either the combined capacity of both halves of said impeller 35 against the pressure created by one of them, or the capacity of one against the combined head of both.

Figs. 3 and 4 represent the same general 40 construction as that shown in Figs. 1 and 2, except that two double service impellers I separated by partition A (fastened in casing C by set-screw Z) are employed and the base M contains manifold passages 2, 3 and 45 4 and ports so that three instead of two different combinations of service are possible. In other words since there are two double service, or in effect, four single impellers, all four may be operated in parallel, 50 or in series, or else the four impellers may be operated in parallel pairs and those pairs in series.

The casing C is provided with four volute or discharge passages, each having a discharge port 5. The casing is adapted to be

turned in the base member M and the ports or passages 5 may, therefore, be brought into register with either of the three rows of passages 2, 3 or 4. The ports 5 when in register with the passages 4 permit all four 70 impellers to operate in parallel, as shown in Figs. 3 and 4, thereby discharging four volumes of water under a pressure equal to that created by one impeller, for instance, ten pounds pressure.

Registry of the ports 5 with the passages 3 causes the first pair of impellers to discharge their combined two volumes in series through the second pair of impellers, thereby doubling the water pressure or increasing it to twenty pounds but reducing the volume by one-half. Registry of the ports 5 with the passages 2 causes all four impellers to operate in series, thereby decreasing the volume of water to one-quarter but increasing the pressure four times or raising it to forty pounds.

Figs. 5, 6, and 7 illustrate another construction for accomplishing the same result as described in Figs. 1 and 2. In this construction two single impellers I are shown, although one double service impeller could have been employed. The chief difference lies in the fact that the manifold passages instead of being stationary and contained in the base are embodied in a separate movable section consisting of manifold G mounted on pump casing C. A slot B in manifold G permits it to slide on seat J when machine screw U is loosened; while tightening the latter serves to hold manifold G in place. In this design the top of casing C is shaped so as to form a receptacle V for water to seal the joint formed between manifold G and seat J. Manifold G contains passages W and X and is designed to slide longitudinally on plane surface of seat J to position indicated by dash and dot lines in Fig. 7 when it is desired to operate impellers I in parallel. The position of manifold G shown in Figs. 5, 6, and 7 is such as to connect impellers I in series. In this position water enters main suction opening S passing through passage T to impeller passage O and out through passage 115 N and port Q into manifold passage X. Passage X leads through port L and passage K to impeller passage E and from there through discharge passage P to main discharge opening D. When manifold G is 120 moved to position shown by dot and dash lines H in Fig. 7 it is clear that the manifold passage W will connect the two entrance openings of impellers I together through passages T and K communicating with main suction opening S; and manifold passage X will connect the two discharge ports Q and R with main discharge opening D, thereby connecting impellers I in parallel.

Where the phrase "two or more impellers" 130

is used in the claims it will be understood to mean either two or more independent impellers, or one or more compound or double service impellers containing two or more independent streams capable of being combined in parallel or series.

It will also be understood that the invention is not to be limited to the exact form or arrangement of parts in either of the constructions shown in the accompanying drawings, but that modifications therein may be made without departing from the invention as defined by the claims.

I claim:

15. 1. In a centrifugal or similar pump having one or more double-service impellers each capable of series or parallel operation, a suction and a discharge passage formed in the pump connecting with each side of each 20 impeller, and turnably mounted means for changing the connection of said passages so that the several sides of said impellers may be operated in series, in parallel, or in multiple series.
25. 2. In a centrifugal or similar pump having one or more double-service impellers, each capable of series or parallel operation, a suction and a discharge passage formed in the pump connection with each side of each 30 impeller, and means for changing the connection of said passages so that the several sides of said impellers may be operated in series, in parallel, or in multiple series.
35. 3. A pump comprising a pair of casing sections movable one with relation to the other, a plurality of impellers journaled to rotate in one of said casing sections, suction and discharge passages formed in the casing carrying the impellers and communicating 40 with the impellers, suction and discharge passages formed in the other casing section adapted to register with the suction and discharge passages formed in the impeller casing, and means for moving one 45 casing section with relation to the other to bring different ports into register to permit the impellers to operate in parallel, in series or in multi-series.
50. 4. A centrifugal pump comprising a base section having a main suction and discharge opening and a plurality of communicating suction and discharge passages formed therein, an impeller casing movable with relation to the base section, a plurality of impellers mounted in the impeller casing, a plurality of suction and discharge passages formed in the impeller casing communicating with the impellers and also with the suction and discharge passages in the base 55 section, and means for moving the impeller casing with relation to the base section to bring different ports into register to permit the impellers to operate in parallel, in series, or in multi-series.
60. 5. In a centrifugal or similar pump hav-

ing two or more impellers, a pump casing having independent suction and discharge passages formed therein for each of said impellers, a base section with passages formed therein having ports arranged to 70 connect the various combinations of said suction and discharge passages in said pump casing so as to connect impellers in series, in parallel, or in multiple series, by changing the relative position of said pump cas- 75 ing and said base section.

6. A pump comprising a pair of casing sections turnably mounted one with relation to the other, a plurality of impellers journaled to rotate in one of said casing sections, suction and discharge passages formed in the casing containing the impellers communicating with the impellers, suction and discharge passages formed in the other casing section adapted to register with the suction and discharge passages in the impeller casing, and means for turning one casing section with relation to the other to bring different ports into register to permit the impellers to operate in parallel, in series, 90 or in multi-series.

7. A centrifugal pump comprising a base section having a main suction and a discharge opening formed therein, a plurality of communicating suction and discharge 95 passages, an impeller casing turnably mounted with relation to the base section, a plurality of impellers journaled to rotate in the impeller casing, a plurality of suction and discharge passages formed in the im- 100 peller casing communicating with the impellers and also with the suction and discharge passages in the base section, and means for turning the impeller casing with relation to the base section to bring different ports into register to permit the impellers to operate in parallel, in series, or 105 in multi-series.

8. A centrifugal pump having a double impeller and a casing having communicating 110 passages formed therein for connecting the two sides of said impeller in series.

9. In a centrifugal pump, a plurality of impellers, an impeller casing in which said impellers are mounted having suction pas- 115 sages formed therein connecting with the impellers and discharge passages formed therein into which the impellers discharge, a base member supporting said casing having a plurality of passages formed therein 120 adapted to connect with the discharge and suction passages in the impeller casing, and means for changing the position of the impeller casing with relation to the base member and the passages formed therein to permit the impellers to be operated in parallel, 125 in series, or in multi-series.

10. In a centrifugal pump, a plurality of impellers, an impeller casing in which said impellers are mounted having suction pas- 130

- 1 sages formed therein connecting with the impellers and discharge passages formed therein into which the impellers discharge, a base member supporting said casing having a plurality of passages formed therein adapted to connect with the discharge and suction passages in the impeller casing, and means for turning the impeller casing with relation to the base section and the passages formed therein to permit the impellers to be operated in parallel, in series, or in multi-series. 5
- 10 11. In a pump, a plurality of impellers, a pair of casing sections movable one with relation to the other, each of the casing sections having passages with communicating ports formed therein, means for moving one casing section with relation to the other so as to bring suitable ports of one casing into register with selected ports of the other casing so as to permit the impellers to operate in parallel, in series, or in multiple series, and means for maintaining a water seal between said movable casing sections. 20
- 15 12. In a centrifugal or similar pump, a pump casing surrounding the impellers thereof and having an outside cylindrical surface or seat with ports formed therein connecting independently with the suction or discharge of each impeller requiring different connections, a base section having a cylindrical surface of contact with said cylindrical seat of said casing, manifold passages in said base sections having ports arranged in said surface of contact to connect said ports of said casing in various combinations by rotating said casing on its longitudinal axis to selected positions, so as to connect said impellers in series, in parallel, 30 or in multiple series, and a main suction and a main discharge opening formed in said base. 35
- 20 13. In a centrifugal or similar pump, a pump casing surrounding the impellers thereof and having an outside cylindrical surface or seat with ports formed therein connecting independently with the suction or discharge of each impeller requiring different connections, a base section having a main suction and a main discharge opening formed therein and a cylindrical surface of contact with said cylindrical casing, a receptacle for holding water over said surface of contact, manifold passages formed in said base having ports arranged in said surface adapted to connect with the ports in the casing in various combinations by rotating said casing on its longitudinal axis to selected positions, so as to connect said impellers in series, in parallel, or in multiple series. 50
- 25 14. In a centrifugal or similar pump, a pump casing having suction and discharge passages formed therein with ports in the outside surface of said casing, a base with a main suction and a main discharge opening formed therein and passages with ports in the surface of contact between said casing and said base, said ports connecting the ports in the casing with said main suction and main discharge openings in the base. 70
- 30 15. In a centrifugal or similar pump, a pump casing having suction and discharge passages formed therein with ports in the outside surface of said casing, a base with a main suction and a main discharge opening formed therein and passages with ports in the surface of contact between said casing and said base, said ports connecting the ports in the casing with said main suction and main discharge openings in the base, and a receptacle for holding water over said surface of contact in order to seal same. 75
- 35 16. In a centrifugal or similar pump, a casing surrounding the impellers thereof and having an outside cylindrical surface or seat with ports formed therein connecting with said impellers, an open-top base section having a cylindrical surface of contact with said cylindrical seat of said casing, 80 ports formed in said surface of contact of said base communicating with the ports in the casing, and a main suction and a main discharge opening formed in said base having communicating passages connecting with the ports of said surface of contact. 85
- 40 17. In a centrifugal or similar pump, a double impeller having two completely independent stream passages formed therein separated by a transverse partition, a suction opening and vanes having the usual circumferential discharge located each side of said transverse partition, a peripheral surface between and peripheral surfaces outside of the two said circumferential discharges, said peripheral surfaces being designed to run close to the inside cylindrical surface of the pump casing in order to minimize leakage between the two said circumferential discharges themselves and between each circumferential discharge and its corresponding suction opening. 90
- 45 18. In a pump, a plurality of impellers, a pair of casing sections movable one with relation to the other, each of the casing sections having passages with communicating ports formed therein, and means for moving one casing section with relation to the other so as to bring suitable ports of one casing into register with selected ports of the other casing so as to permit the impellers to operate in parallel, in series or in multiple series. 100
- 50 19. In a pump, a plurality of impellers mounted in casing sections movable with relation to each other, passages with ports formed in each of the casing sections, and means for moving the casing sections with relation to each other to bring suitable ports of one casing into register with selected 105
- 55 130

ports of another casing so as to permit the impellers to operate in parallel, in series, or in multiple series.

20. A pump having a double impeller, a 5 casing section having passages and communicating ports formed therein, a manifold section having passages with ports formed therein, and means for moving one section with relation to the other in order to bring 10 different ports into register so as to permit the two sides of the double impeller to operate in parallel or in series.
21. In a centrifugal or similar pump, a 15 double impeller having two completely independent stream passages formed therein separated by a partition, a suction opening and vanes having the usual circumferential discharge located each side of said partition, a peripheral running face formed between

the annular discharge openings of the impeller, and an annular peripheral flange on each side of the impeller having running faces formed thereon.

22. In a centrifugal or similar pump, a 25 double impeller having two completely independent stream passages formed therein separated by a partition, a suction opening and vanes having the usual circumferential discharge located each side of said partition, a peripheral running face formed between the annular discharge openings of the impeller, an annular, outwardly projecting flange formed on each side of the impeller around each suction opening, and a second concentric annular flange on each side of the 30 impeller, said inner and outer annular flanges having running faces formed thereon.

WILLIAM DOUGLAS CARTER.
